COMBINED TELEPHONE STAND AND
UTILITY CABINET

Joseph Conrad, New Orleans, La.

Application November 9, 1945, Serial No. 627,687

1 Claim. (Cl. 312—272)

1 The present invention relates to a combined telephone stand and utility cabinet embodying an article of furniture including a cabinet construction formed with compartments, drawers and sliding trays adapted for holding various articles for storing in the cabinet, the top of the cabinet being adapted for supporting a telephone thereon and also providing sliding panels in both the top and front of the cabinet and adapted to contain frequently used telephone numbers for quick reference by persons using the telephone, as well as for containing emergency telephone numbers by means of which emergency calls may be made without loss of time.

An important object of the present invention is to provide a combined telephone stand and cabinet of this character in which the sliding panels at the top and front of the cabinet are connected to each other for simultaneous opening and closing movement so that upon an outward movement of one of the panels from the cabinet, the other of said panels will likewise be moved outwardly into a position for reading the telephone numbers carried thereby.

A further object of the invention is to provide a recess in the top of the cabinet in which an adapter may be placed for receiving and supporting bases of telephones of various shapes, and whereby the telephone is supported against sliding movement on the cabinet while a number is being dialed.

A still further object of the invention is to provide a writing shelf slidably mounted in the upper portion of the cabinet and movably outwardly from either side thereof for use by either a right handed or left handed person.

Another object of the invention is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and wherein:

Figure 1 is a front elevation of a combined stand and cabinet illustrative of the invention.

Figure 2 is a side elevation of the combined stand and cabinet showing panels in outwardly extended position.

Figure 3 is an isometric projection of the cabinet top.

2 Figures 4 and 5 are top plan views of the adapters for accommodating telephones of various sizes and shapes; and

Figure 6 is a top plan view of the cabinet with the cabinet top and top drawer removed.

Referring now to the drawing in detail, wherein for the purpose of illustration I have disclosed a preferred embodiment of the invention, the numeral 5 designates a cabinet body which may be of square shape in cross-section or of any other desired cross-sectional shape and including a top 6 to the rear portion of which is secured a lamp standard 7 by means of a flanged base 8 for supporting a lamp shade 9 at its upper end in a position overlying the top of the cabinet. An extension cord 10 is attached to the lamp standard for connection with a suitable outlet.

The top 6 is also formed with an elongated opening 11 providing communication with the interior of the cabinet and within which is suitably secured a pair of spaced parallel vertically extending guides 12 extending downwardly from the under side of the top of the ends of the opening 11.

A panel 13 is slidably mounted in the guides 12 for vertical movement through the opening 11 and adapted for movement into and out of a concealed position in the cabinet. To the front of the panel 13 is attached or otherwise suitably displayed a list of telephone numbers designated at 14 and which preferably comprise emergency telephone numbers, such as police, fire department, ambulance, doctors' phone numbers, and the like.

A shelf 15 is slidably mounted in an opening 16 in the front of the cabinet and is provided at its outer edge with pull knobs 17. The shelf 15 is also adapted to contain frequently used telephone numbers on its upper surface as indicated at 14'.

The inner edge of the shelf 15 and the lower edge of the panel 13 are connected with two flexible cords or cables 18 extending over pulleys 19 secured within the cabinet and arranged so that an outward sliding movement of the shelf or panel 15 will cause an upward movement of the panel 13, whereby to raise the latter to its exposed position when the shelf or panel 15 is pulled outwardly. The panel 13 will gravitate downwardly in the guides 12 on an inward movement of the shelf or panel 15.

The top 6 is formed in its upper surface adjacent the front edge thereof with a recess 20 of polygonal shape or noncircular construction adapted for receiving a similarly shaped block

or boss 21 on the under side of an adapter 22 or 23, as illustrated in Figures 4 and 5 of the drawing and detachably associated with the cabinet.

The adapter 22 comprises a flat plate formed with a recess 24, within which the base of a dial telephone 25 corresponding to the shape of the recess 24 may be positioned. The adapter 22 has a square-shaped recess therein while the adapter 23 is formed with a circular recess 26 in its upper surface to receive a telephone having a correspondingly shaped base.

By seating the base of the telephone in the adapter, the telephone is prevented from sliding on the top section of the cabinet while dialing the telephone.

A writing shelf 27 is slidably mounted in an opening 28 extending transversely through the upper portion of the cabinet and outwardly at each side thereof. Each end of the shelf 27 is formed with a knob or handle 28 by means of which the shelf may be moved outwardly at either side of the cabinet to provide a writing shelf or support for either a right or left handed person while using the telephone. The upper surface of the shelf 27, adjacent each end thereof, is provided with one or more recesses 29 adapted to contain a writing pad, pencils or other writing equipment.

In the front of the cabinet below the shelf 15 is mounted a sliding drawer 30 adapted for holding a telephone directory and below the drawer 30 is a sliding utility drawer 31 adapted for holding smoking equipment or the like, as shown at 32.

The lower portion of the front of the cabinet is provided with a pair of hinged doors 33 to afford access to the interior of the lower portion of the cabinet and which may be used as a storage space.

It will be apparent from the foregoing that the combined telephone stand and utility cabinet provides a suitable support for a telephone while the latter is held against sliding movement during the dialing of a number and the panels 13 and 15 slidably carried in the cabinet provide easily accessible and quick means for determining emergency and frequently used telephone numbers without incurring delay in looking up the numbers in the telephone book or directory.

It is believed that the details of construction, manner of use and advantages of the device will be readily understood from the foregoing without further detailed explanation, and further it

will be noted that this device is simple in construction and extremely practical owing to the fact that the parts involved in this construction will not readily become out of order.

It is to be understood, however, that even though I have herein shown and described a preferred embodiment of my invention, the same is susceptible of certain changes fully comprehended by the spirit of the invention as herein described, and the scope of the appended claim.

Having thus described the invention, what I claim is:

In a rectangular cabinet body having a top and a front with a rectangular opening in said top spaced from and substantially parallel to said front and a rectangular opening in said front adjacent and substantially parallel to said top, guides disposed one at each end of aid top opening extending inwardly of said body, a panel slidable in said guides for movement substantially perpendicular to said top between a concealed position within said cabinet and an exposed position in which it extends above said top, a shelf slidable through said front opening substantially perpendicular thereto between a concealed position within said body and an exposed position in which it extends outwardly from said front, and flexible means operatively connecting said shelf and said panel whereby they are simultaneously exposed and concealed, said flexible means comprising a pulley rotatably mounted in said cabinet, and a cord trained over said pulley and connected at one end to the inner end of said shelf and at its other end to the lower end of said panel.

JOSEPH CONRAD.
